OF ST. JOSEPH, MICHIGAN, A CORPORATION OF MICHIGAN.

POP-GUN.

1,287,780.

Specification of Letters Patent. Patented Dec. 17, 1918.

Application filed December 17, 1917. Serial No. 207,477.

To all whom it may concern:

Be it known that I, ORA A. STANARD, a citizen of the United States of America, and resident of St. Joseph, county of Berrien, 5 and State of Michigan, have invented a certain new and useful Improvement in Pop-Guns, of which the following is a specification.

This invention relates to pop-guns of that kind in which means are provided for automatically drawing the cork back into the muzzle of the gun, when the plunger is retracted to place the gun in condition for another discharge, so that the placing of the 15 cork in the muzzle of the gun, by hand, in the ordinary manner, will not be necessary.

Generally stated, the object of the invention is to provide a novel and improved pop-gun of the foregoing general character.

20 A special object is to provide an improved construction and arrangement whereby the spring which operates the plunger is also employed for drawing the cork back into the muzzle of the gun, so that this restoration 25 of the cork is accomplished by yielding pressure thereon, and whereby the cork-restoring-connection, after the cork is pressed into the end of the barrel, is then automatically moved forward a distance, by the movement 30 of the hand-lever which compresses the spring and thereby places the gun in condition for the discharge, so that when the plunger is released, by pulling the trigger, the cork-restoring-connection will not interfere 35 with the discharge of the cork.

Another object is to provide an improved construction and arrangement which will obviate the necessity of using certain devices and features of construction heretofore considered necessary and desirable in a pop-gun 40 of this kind.

It is also an object to provide certain details and features of construction and combinations tending to increase the general 45 efficiency and desirability of an automatic reloading pop-gun of this particular construction.

To these and other useful ends the invention consists in matters hereinafter set forth 50 and claimed.

In the accompanying drawings:—

Figure 1 is a side elevation of a pop-gun embodying the principles of the invention, showing a portion of the gun in longitudinal

section, and showing the gun in normal condition. 55

Fig. 2 is a similar view, showing the forward end or muzzle portion of the gun in longitudinal section, as well as the rear portion, and showing the plunger retracted and the cork restored to its operative position in the muzzle of the barrel.

Fig. 3 is a perspective of the cork-restoring-connection.

Fig. 4 is a view similar to Fig. 1, but showing the muzzle portion of the gun in longitudinal section, and the rear portion in side elevation, and showing the plunger retracted and the spring compressed and the gun in position to be discharged. 70

As thus illustrated, the invention comprises a gun stock A of any suitable form or character, and a barrel B of any suitable known or approved form secured thereto in the usual or any suitable manner. Said barrel contains the ordinary plunger C, which is operated by the coil-spring D and which is provided with a rearwardly extending plunger-rod c having a down-turned rear portion 1 for engagement with the action-lever E, as well as with the trigger F, which latter is of the usual or any suitable form. Also, the barrel contains a sliding abutment G, which is of the usual or ordinary form except for the longitudinal slot g near the front end thereof. The spring D, it will be seen, is interposed between the head of the plunger and the front end of said abutment, and the rear end of the latter is adapted to engage the cam e on the front end of the action-lever. Except for the slot g, the gun thus far described is of any ordinary or suitable character, and is adapted to discharge the cork H in the well known manner. 85

In order, however, that the gun may be self-loading—that is to say, in order that the cork H may be automatically restored to operative position in the end of the gun, a cork-restoring-connection I is disposed along one side of the barrel, near the bottom thereof, and is provided at its rear end with an up-turned portion i to engage the slot g, and at its forward end with an up-turned end portion provided with a disk 2 for engaging the outer end of the cork. Furthermore, the muzzle of the barrel is provided with an extension b having an open end and a top slot 3, and having a longitudinal side

slot 4 near the bottom thereof. The upturned forward end portion of the cork-restoring connection I slides in the slot 4, and in addition the barrel of the gun is provided with a longitudinal slot 5 in which the portion *i* of the cork-restoring-connection slides back and forth. It will be seen that this portion *i* is enlarged at its end, and in this way this portion can be inserted 10 through the slot *g*, by holding the connection I at right angles to the barrel, and can then be turned around to bring the head 6 of this end portion *i* crosswise of the slot *g*, when the connection I is moved into a position parallel with the barrel, thus preventing detachment of said connection from the sliding abutment G previously described.

It will be seen that the action-lever E is pivoted, in the ordinary manner, at 7, while 20 the trigger F is pivoted at 8 and yieldingly held in position by a spring 9 interposed between the front end of the stock of the gun and the rear edge of said trigger.

With the parts in the condition shown in 25 Fig. 1, the cork has been discharged and the gun is in normal condition. When the action-lever E is swung downward and forward, in the usual manner, as shown in Fig. 2, the plunger-rod *c* and the plunger C are 30 drawn backward or retracted (see Fig. 2) until the portion 1 of the plunger-rod is caught and held by the trigger F, so that the action-lever E is then ready to be drawn backward against the stock of the gun. 35 When this is done, the cam *e* engages the rear end of the abutment G, forcing the latter forward into the position shown in Fig. 4, thus compressing the spring D against the rear side of the plunger-head, so 40 that the gun is then ready to be discharged. When the plunger is drawn back, see Fig. 2, thus drawing the spring and abutment backward also, the cork-restoring-connection I is pulled backward, thus causing the 45 cork H to be pressed into the muzzle of the barrel. It will be seen that this is done by a yielding pull exerted through the spring D, so that the connection I can stop moving rearward as soon as the cork is firmly seated 50 in the end of the gun, even though the plunger still has some distance to travel backward before the portion 1 is firmly engaged with the trigger. In this way, the cork is not forced into the end of the barrel any 55 farther than is absolutely necessary, but this distance will be automatically increased, from time to time, as the cork becomes worn or compressed by use; and, thus the spring D serves automatically to take 60 up the wear on the cork, so that the latter will always be firmly pressed into the muzzle of the gun. When the action-lever E is pulled backward against the stock of the gun, as shown in Fig. 4, the cam *e* forces 65 the abutment G forward, to compress the

spring D, and this also moves the cork-restoring-connection I forward, thus advancing the disk 2 sufficiently to prevent it from interfering with the free discharge of the cork, when the trigger is pulled to discharge 70 the gun. In this way, therefore, the action-lever E is not only operative to automatically pull the cork back into the end of the barrel, but is also operative, through the connection of the cork-restoring-connection 75 with the sliding abutment, to advance the disk 2 sufficiently to provide clearance in the hollow extension *b* of the barrel, sufficient to permit free discharge of the cork when the trigger is pulled to release the 80 plunger. The slots 3 and 4 provide openings through which the air escapes, when the cork is discharged, so that the desired sound is insured.

As shown and described, the automatic 85 reloading connection I is attached to the abutment G for the purpose, in this particular case, of automatically restoring the cork H (by "cork" is meant a member of any suitable material which will serve the 90 purpose of the ordinary pop-cork) to its operative position in the muzzle of the barrel of the gun; but, of course, it will be understood that this connection I can be attached to the sliding abutment for any 95 suitable or desired purpose, depending upon the character of the gun, and may be employed for automatic reloading purposes, in any suitable or desired manner; and the invention is not, therefore, limited to the 100 exact construction shown and described.

Thus the cork, when discharged, is caught and held by the fixed extension *b* of the barrel of the gun, and the disk 2, when drawn backward by the operation of the hand-lever, (when the plunger is retracted) will push the cork into the muzzle of the gun. In this way, therefore, it is not necessary to restore the cork by hand, in the usual or ordinary manner, the reloading being automatic in character and being brought about merely by the operation of the hand-lever, but in such a manner that the discharge of the cork is sufficiently free and unrestricted to insure the desired popping action when 115 the trigger of the gun is pulled. The cork-restoring-connection does not retain the cork in operative position, but merely draws it into such a position, and is then moved forward, in the manner shown and described, to 120 provide ample clearance for the free discharge of the cork when the plunger is released.

What I claim as my invention is:—

1. A pop-gun wherein the cork is discharged by mechanism comprising a plunger operated by a spring, a lever and a sliding abutment for compressing said spring, after said lever is first operated to fully retract said plunger, characterized by this, to 130

wit:—that a connection is provided to engage said cork and for actuation through said spring to automatically and yieldingly restore said cork to operative position by 5 movement of said lever.

2. A structure as specified in claim 1, said cork-restoring-connection being disposed outside of and longitudinally of the barrel of the gun, and the rear end of said connection being attached to said sliding abutment, so that said connection slides forward when said sliding abutment is actuated forward to compress the spring.

3. A structure as specified in claim 1, and 15 a fixed extension on the end of the muzzle of the barrel of the gun, providing a retainer for the cork and a guide for the forward end of said cork-restoring-connection, and the rear end of said connection being 20 connected with said sliding abutment, whereby the front end of said connection slides forward in said extension when said lever is operated to compress the spring.

4. In a pop-gun, the combination of a barrel, a member to be forced from the muzzle 25

of the barrel to produce the popping sound, mechanism including a spring to compress the air within the barrel and thereby discharge said member from the end of the barrel, and a connection having its forward end 30 provided with means to engage said member and having its rear end so connected with said mechanism for actuation through said spring that its said forward end first slides backward to yieldingly force said 35 member into operative position, and then slides forward to provide clearance for the discharge of said member, when said mechanism is operated to place the gun in condition for discharge.

5. In an air-gun, the combination of a plunger, mechanism including a spring and a sliding abutment for compressing said spring to operate said plunger, and an automatic reloading connection attached to 45 and operated by said abutment.

Signed by me at St. Joseph, Berrien county, Michigan, this 6th day of December, 1917.

ORA A. STANARD.
